ROAD PLANER OR DRAG

Franklin E. Arndt, Galion, Ohio, assignor to The Galion Iron Works & Mfg. Co., Galion, Ohio, a corporation of Ohio

Application August 26, 1930, Serial No. 477,875
Renewed November 9, 1933

15 Claims. (Cl. 37—153)

This invention relates to road scrapers and particularly to road drags of that character wherein a fore truck is used and a scraper supporting frame is used pivotally supported adjacent its forward ends upon the fore truck, and for vertical adjustment, the rear of the supporting frame being mounted upon wheels for vertical adjustment, the fore truck being adapted to be connected to a tractor and the frame supporting the scrapers to be adjusted vertically by means located adjacent the driving station of the tractor.

One object of the present invention is to provide a cranked axle for the rear wheels and provide means whereby the cranked axle may be raised or lowered and particularly to provide means whereby the cranks on the axle may be adjusted relative to the axle itself so as to cause the supporting frame to be raised at one side higher than the other to permit the drag to be used on a crown road or for crowning, and a further object in this connection is to provide a device of this character which may be readily adjusted and readily held in adjusted position.

Another object is to provide improved means whereby a single control may be used for raising or lowering simultaneously the forward and rear ends of the frame and whereby the connections for lifting the forward end of the frame may be so adjusted as to permit the frame to be relatively tilted for crowning purposes.

Other objects will appear in the course of the following description.

My invention is illustrated in the accompanying drawings, wherein:

35 Figures 1 and 1a together constitute a side elevation of a drag or planer constructed in accordance with my invention;

Figure 2 is a fragmentary top plan view of the rear portion of the drag or planer;

40 Figure 3 is an enlarged fragmentary section on the line 3—3 of Figure 2;

Figure 4 is an elevation of the segment and wheel supporting arm, the shaft being in section;

45 Figure 5 is a longitudinal sectional view through the casing which houses the gear assembly for vertically adjusting the rear frame; and

Figure 6 is a section on the line 6—6 of Figure 1a.

Figure 7 is a section on the line 7—7 of Figure 2.

Referring to these drawings, 10 designates longitudinal beams of a scraper supporting frame, these beams being connected by suitable transverse beams 11 at any desired intervals and carrying scraper blades 12 and a rear adjustable

scraper blade 13 as described in my co-pending application, Serial No. 477,876 filed on the 26th day of August, 1930.

The fore truck is designated generally 14 and carries, of course, the forward wheels 15. This fore truck has the tongue 16 whereby it may be connected to the tractor. Draw bars 17 are connected to the fore truck by a fifth wheel connection 18, these draw bars extending upward and then downward and rearward and being pivotally connected to upwardly extending irons or ears 19 on the beams 10. It will be understood that the draft bars are connected at intervals by cross beams 20 at any suitable points.

The forward end of the frame which includes 15 the beams 10 is connected to chains 21 in turn connected to strap links 22 which are provided with a series of bolt holes. These are connected to forwardly extending arms 23 mounted upon a transverse shaft 24 carried by the draft bars. 20 This shaft is actuated by a gear 25 engaged by a pinion 26 on the shaft 27 which carries a worm wheel engaged by a worm 28. The shaft 24 is also provided with an upwardly and rearwardly extending cam 29 connected by a chain 30 to a 25 spring 31, this spring in turn being connected by the linked rod 32 to an angle 33 mounted upon the rear frame and more specifically connected to the beams 10 midway of the length of these beams, this spring 31 acting to urge the 30 shaft 24 in a direction to lift upward on the blade or scraper supporting frame. The worm 28 is connected to manually operable controlling means as will be later stated.

It should be understood that while I have illustrated only one crank arm 23 connected by the adjustable strap link 22 and the chain 21 to the multiple bladed structure comprising the frame 10, a similar arrangement is mounted on the opposite side of the machine, there being a 40 crank arm 23 at each end of the transverse shaft 24. The gear 25 and the rearwardly extending arm 29 are secured to the transverse shaft intermediate the ends of the latter. It will thus be seen that by means of the adjustment mechanism associated with the rear wheels, as shown in Figs. 2, 3 and 4, transverse tilting of the rear portion of the frame 10 may be effected, and by means of the adjusting mechanism shown in Fig. 1a, transverse tilting of the forward portion of 50 the frame 10 may be effected. Such transverse tilting is particularly desirable for road crowning purposes. By means of the worm gearing connections 28 and 42 to the transverse shafts 24 and 34, either shaft may be rocked independently of 55

the other to tilt the frame longitudinally from either end or both shafts may be rocked simultaneously to effect variation in elevation of the frame 10 as a whole.

5. It will be seen that the arms 23 may be engaged with the links 22 at any desired point and that a link may be taken up on one side to thus tilt the frame.

The means for lifting the rear end of the frame 10 comprises a transverse shaft 34. This shaft has keyed upon it at its opposite ends the sectors 35 so that these sectors will turn with the shaft. Loosely mounted upon each shaft inward of the sectors are the crank arms 36, each carrying a 15 rear wheel 37.

Each sector 35 has the outwardly projecting lugs 38 through which pass the screws 39 which engage on opposite faces of the corresponding arm 36. A screw 39^a passes through an aperture formed in the middle of the sector (or a plurality of apertures disposed in a series transverse to the arm 36) this screw 39^a acting as a set screw to assist in holding the corresponding arm 36 in proper adjusted engagement with the 20 corresponding sector 35. For the purpose of rotating the shaft 34, I mount upon the shaft the segment gear 40 engaged by the pinion 41 mounted upon a shaft carrying a worm wheel which is engaged by a worm 42. The shaft 34 25 also carries an upstanding lever 43 from which extends a tension means comprising the chain 44, the spring 45 and the link 46. Said link 46 is anchored to the forward end of the frame 10 by an angle iron 47. The nut 48, screw-threaded 30 on said link 46, provides for adjustment of the tension of the spring 45. Similar means provide for adjustable tension on the spring 31. In the rotation of the shaft 34 to increase the height of the frame 10 above the ground, the tension of the spring 45 tends to reduce the work necessary 35 to perform this operation as said spring 45 is tensioned to aid such movement.

It will be seen that the spring 45 acts to turn the shaft 34 in a clockwise direction so as to exert a downward and rearward depressing force on the arms 36 and thus lift or assist in lifting the 40 scraper.

The shaft of the worm 42 is connected by a universal joint 49 to a shaft section 50 which 45 extends upward and forward and has a universal joint connection to a shaft section 51 in turn extending upward and forward being mounted in suitable supports upon the draw bars and being connected by a universal joint 52 to a control shaft 53 extending into a casing 54. The 50 worm 28 is connected by a universal joint 55 to a shaft section 56 which extends upward and forward and is connected by a universal joint 57 to a shaft section 58 parallel to the shaft section 53 and extending into the casing 54, as shown in Fig. 5.

Entering the forward end of the casing is a control shaft 59 connected by a universal joint to a shaft section 60 extending forward and carrying a hand wheel, the shaft section being telescopic and having means whereby it may be lengthened or shortened. The shaft 59 is longitudinally slidable within the head of the casing 54 and carries upon it a gear wheel 61 65 adapted to mesh with a gear wheel 62 keyed on shaft 59 or with a loose gear wheel 63 meshing with a gear wheel 64 on shaft 58 or with gears 62 and 63 simultaneously. The shaft section 59, as before stated, is slidable to these three positions. In the position shown in Figure 5, the gear

wheel 61 meshes both with the gear wheel 62 and the gear wheel 63 and thus rotation is communicated, through gear wheel 62 to shaft 53 and through gear wheel 63 to shaft 58. If the shaft 59 be shoved forward to its forwardmost position, it will disengage from gear wheel 62 to engage gear wheel 63 and thus the rotation of shaft 59 will cause a rotation only of shaft 53 but not cause any rotation of shaft 58. When the shaft 59 is pulled rearward to its full extent, the gear 10 wheel 61 will engage gear wheel 62, but not gear wheel 63 and, therefore, the shaft 53 will be operated but not the shaft 58.

To provide means whereby the shaft 59 may be yieldingly held in any of these three adjusted 15 positions, I provide the shaft 59 with three grooves 59^a and form the hub which projects from the head of the casing 54 with a spring pressed detent ball 54^a engageable in any one of these grooves. It will be seen that by means of this 20 mechanism, either series of shaft sections leading to the two worms may be operated or both of them may be operated at the same time and either or both of the lifting mechanisms may be actuated, 25 either separately or at the same time.

When it is desired to use this drag on a crowned road or in crowning a road, it is necessary, of course, that one side of the frame should be lowered relative to the other side of the frame and to this end, I have provided the adjustable links 20 30 35 30^a and the means which I have described with relation to the arms 36 whereby the arms may be turned with relation to the shaft 34. By turning the arm from a middle position, it is obvious that that side of the frame will be lowered.

To accomplish this, the screw 39^a is loosened and then one of the screws 39 is backed off while the other screw is turned inward until the angular adjustment of the arm 36 relative to the shaft 34 has been made and then the lock nuts on the 40 screw 39 are turned home, thus locking the screws in their adjusted position and then the binding screw 39^a is turned home, thus holding the corresponding segment 35 in its adjusted relation to the arm 36. Thereafter when the rear frame is 45 raised or lowered, the frame will move practically evenly at front and rear, but one side of the frame will always be lowered relative to the opposite side of the frame until the parts are readjusted so that the scraper supporting frame is horizontal. 50

This raising or lowering of the frame both at front and rear is assisted by the equalizing springs 31 and 45 which equalizes the strain upon the lifting mechanism. 55

The shaft 60 at its forward end extends through a bearing 65 adjustably mounted upon a vertical support 66 connected to bracket 67 mounted upon tongue 16. Thus the tongue 16 may be raised or lowered or vertically adjusted to suit tractors of 60 different heights and at the same time the shaft 60 may be kept in a horizontal position or disposed in the most convenient position for the operator standing upon the tractor which is connected to the tongue 16 and disposed immediately in advance of the scraper. The tongue is shown as being supported by a spring 68 connected by a shackle plate 69 to the forward end of the draw bars. 65

I have not attempted to describe all the braces, truss rods and other like parts and these are obvious and furthermore might be varied in many ways without departing from the spirit of the invention as defined in the appended claims. 70

While I have illustrated means for raising or lowering the front and rear ends of the frame 75

formed of the members 10 in connection with a drag or planer, I do not wish to be limited to this use, as it might be applied to other implements of like general character.

5. It will be noted that I have provided a one piece axle and that I mount upon the extremities of this axle the crank arms supporting the rear wheels, these crank arms being loosely mounted in the axle. By using a one-piece axle, I render the 10 structure much more rigid than if a two piece axle were used with means for separately adjusting each axle.

It will also be seen that by one hand wheel, 15 the driver can control all adjustments of the blades without leaving the station or tractor and that I have provided a four wheel drag or planer which may be easily handled and in which the blades are quickly adjusted to varying ground conditions, thus permitting the operator to raise 20 the blades for soft spots or utilize the weight of the machine when the road is hard. It will likewise be seen that the arched draw bars permit the planer or drag to be turned at a relatively short radius.

25. While I have illustrated a construction which has been found to be particularly effective in actual practice, I do not wish to be limited to the details except as stated in the appended claims.

I claim:

30. 1. In a road planer or drag, a rear blade supporting frame, a fore truck having draw bars pivotally connected at their rear ends to the rear frame, a transversely extending axle on the rear frame, crank arms loose on the axle and carrying supporting wheels, mechanism on the fore truck for raising or lowering the forward end of the frame, mechanism on the frame for oscillating said axle to thereby raise or lower the frame, manually controlled means for operating both of said 35 mechanisms, means whereby the crank arms may be independently shifted around the axle and held in shifted position, and means whereby one side or the other of the forward end of the rear frame may be raised or lowered relative to the lifting mechanism therefor.

45. 2. In a road planer or drag, a rear blade supporting frame, a fore truck having draw bars pivotally connected at their rear ends to the rear frame, a transversely extending axle on the rear frame, crank arms loosely mounted upon the ends of the axle and carrying supporting wheels, a shaft on the fore truck having arms operatively connected to the forward end of the frame, mechanism on the rear frame for oscillating the axle 50 thereof to thereby raise or lower the rear frame, manually controlled means for oscillating said first named shaft and mechanism for oscillating said axle, and means whereby the crank arms may be independently shifted around the axle and held in shifted position, and means whereby the operative connections at the opposite ends of the shaft may be shortened or lengthened to thus 55 raise one side or the other of the forward end of the rear frame.

60. 3. In a road planer or drag, a rear blade supporting frame, a fore truck having upwardly arched draw bars pivotally connected at their rear ends to the rear frame, wheels supporting the fore truck and relative to which the fore truck is rotatable in a horizontal plane, a transversely 65 extending axle on the rear frame, crank arms loosely carried thereon, supporting wheels mounted on the crank arms, a shaft on the fore truck having arms adjustably connected to the forward end of the rear frame, operating shafts

extending longitudinally one for the arm carrying shaft and one for said axle, and operatively engaged therewith to rotate the shaft and axle respectively, a single manually operable means for rotating both of said shafts simultaneously, and means whereby the crank arms on the rear shaft may be independently shifted around the axle and held in shifted position.

5. In a road planer or drag, a rear blade supporting frame, a shaft extending transversely 10 across said frame, radially disposed wheel supported crank arms loosely mounted on the shafts adjacent the ends thereof, segmental members mounted upon the shaft to turn therewith and having adjustable set screws bearing on opposite 15 edge faces of each arm whereby to rotatively adjust either arm relative to the shaft.

5. In a road planer or drag, a rear blade supporting frame, a shaft extending transversely 20 across said frame, radially disposed wheel supported crank arms loosely mounted on the shafts adjacent the ends thereof, segmental members mounted upon the shaft to turn therewith and having adjustable set screws bearing on opposite 25 edge faces of each arm whereby to rotatively adjust either arm relative to the shaft, each segmental member having a set screw passing through the segmental member and bearing against the face of the corresponding arm.

6. In a road planer, a rear blade supporting 30 frame, a fore truck having draw bars pivotally connected therewith, an axle mounted on the supporting frame and having radial arms carrying supporting wheels, a shaft mounted on the fore truck and having radial arms operatively connected to opposite sides of the forward end of the frame, worm wheels associated with the shaft and axle respectively and operatively geared thereto, worm shafts extending rearward from the worm wheels, a gear case into which both of 35 said worm shafts extend, an operating shaft extending into the gear case and having a gear wheel engaging a gear wheel on one of said worm shafts, a gear wheel on the same worm shaft meshing with a gear wheel on the other worm shaft, and means for manually rotating the operating shaft.

7. In an implement of the character described, a supporting frame, a fore truck having draw bars connected to the supporting frame and including a bolster, a tongue operatively connected to the fore truck and adapted to be raised or lowered at its forward end with reference to the fore truck, and a controlling shaft extending out over the tongue and mounted for vertical swinging movement, a member extending upward from the tongue, and a bearing for said controlling shaft adjustably mounted upon said member whereby the tongue may be adjusted vertically to suit different heights of tractor and the controlling shaft be disposed in convenient position for operation.

8. In an implement of the character described, a supporting frame, a fore truck having draw bars pivotally connected to the frame, the fore truck 65 including a bolster, a tongue connected to the bolster and extending forward therefrom, the frame having a fifth wheel connection to the fore truck, a controlling shaft extending out over the tongue and formed of telescopic sections whereby 70 the effective length of the shaft may be increased or decreased, a member extending upward from the tongue, and a bearing through which the controlling shaft passes and adjustably connected to said member.

9. In a road planer, a supporting frame, a blade carrying frame vertically movable with relation to the supporting frame, and means for raising or lowering the forward or rear ends of the blade
15. carrying frame including two operating shafts having parallel portions, a housing into which the parallel portions of the shafts extend, a gear wheel keyed upon one of said shafts within the housing, a gear wheel loose upon the other of said shafts in the housing, the second named gear wheel being longer than the first named gear wheel and meshing therewith, a third gear wheel keyed upon the last named shaft, and a longitudinally shiftable controlling shaft entering the housing and a gear wheel thereon, said gear wheel in one position of the longitudinally movable shaft meshing with both the second and the third named gear wheels, in another position of the shaft meshing with only the third named gear
20. wheel and in still another position of the shaft meshing with only the second named gear wheel, and means for yieldably detaining the longitudinally movable shaft in any one of its several positions to which it is shifted.
25. 10. A vehicle comprising the combination with a framework, of a road working implement carried by the framework, a shaft extending transversely across the framework, crank levers connected with the shaft, wheels carried by said 30. crank levers for supporting the framework, means enabling the crank levers to be independently adjusted relative to the shaft to enable a transverse tilting of the framework relatively to the horizontal for adjusting the road working implement relatively to a road surface for crowning operations upon the surface, and mechanism for turning the said shaft to vary the elevation of the framework relative to the road surface for bringing the road working implement into and out of operative engagement with the road surface.
40. 11. A road working machine comprising the combination with a frame, of a road working implement carried by the frame, a shaft extending transversely across the frame, wheels for supporting the frame and interconnected with the shaft, and mechanism for operating the shaft to adjust the elevation of the frame relative to a road surface for moving the road working implement into and out of engagement with the road surface, the said mechanism comprising a segmental gear secured to the axle, a pinion for operating the segmental gear, means for operating the pinion to effect operation of the gear, and equalizing means for facilitating adjustment of the frame.
45. 12. A vehicle comprising the combination with a frame, of road-working means carried thereby, a shaft extending transversely across the frame and integral from end to end, rear supporting wheels, supports secured to the ends of said shaft to rotate therewith, levers carrying said wheels for rotation thereto, said levers being associated with said supports, and means for holding said levers in adjusted positions relative to said supports to effect adjustment in transverse inclination of the rear portion of said frame.
50. 13. A vehicle comprising the combination with a supporting framework, of a road-working implement carried by said framework, wheels for the rear portion of said framework, a single transverse shaft mounted on said framework and adapted to remain permanently intact from end to end at all times, and adjustable supporting mechanism between the end portions of said shaft and said wheels to effect variation in elevation and transverse inclination of the rear portion of said framework relative to the road surface for road leveling and road crowning purposes.
55. 14. A multiple bladed road planer comprising the combination with a frame, of scraper blades distributed about the lower side of said frame, front supporting wheels, drawbars supported at their front ends on said supporting wheels and having their rear ends pivoted to said frame intermediate the ends of the latter, mechanism between said drawbar and the front end portion of said frame for effecting adjustment in elevation and transverse inclination of the front portion of said frame to position said scraper blades for road leveling or road crowning purposes, rear wheels for the rear portion of said frame, a transverse shaft mounted on said frame for 60. rock movements relatively thereto, sector plates secured to the ends of said shaft, crank levers associated with said sector plates and pivotally carrying said rear wheels, mechanism comprising adjustable abutments on said sector plates forwardly and rearwardly of said crank levers for holding the latter individually locked in predetermined adjusted position relative to said sector plates and thereby enable the adjustment of the elevation and transverse inclination of the rear portion of said frame for such road leveling and road crowning purposes, and mechanism connected to said shaft to rock the same to vary the elevation of the rear portion of said frame.
65. 15. A road working machine comprising the combination with a frame, of road-working mechanism carried by said frame, means for supporting the front end portion of said frame for variation in elevation and transverse inclination for road leveling and road crowning purposes, rear wheels for said frame, crank levers pivotally carrying said wheels at their outer ends, a rock shaft journaled on the rear portion of said frame, sector plates secured to the ends of said rock shaft, mechanism for supporting said crank levers at their inner ends on said shafts adjacent to said sector plates for limited rotative adjustment on said shaft relative to said sector plates, mechanism comprising screws on said sector plates in position to abut against the front and rear sides of said crank levers to hold the latter in adjusted positions relative to said scraper blades and said shaft and thereby effect adjustment in elevation and transverse inclination of the rear portion of said frame for such road leveling and road crowning purposes, and actuating mechanism connected to said transverse shaft to rock the same to vary the elevation of the rear end of said frame.

FRANKLIN E. ARNDT.
